L. C. GREEN

BINDER

Filed Sept. 2, 1924

INVENTOR
Lester C. Green

Harry Bowen
ATTORNEY

UNITED STATES PATENT OFFICE.

LESTER C. GREEN, OF SEATTLE, WASHINGTON.

BINDER.

Application filed September 2, 1924. Serial No. 735,302.

To all whom it may concern:

Be it known that I, LESTER C. GREEN, a citizen of the United States, residing at Seattle, in the county of King and State of Washington, have invented a new and useful Binder; and I do hereby declare that the following is a full, clear, and exact specification, such as will enable others skilled in the art to which it appertains to make and use the same.

The invention is a clip binder for checks or the like in which both ends of the clip are rigidly attached to the back of the binder.

15 The object of the invention is to provide a binder for checks or the like in which it will be impossible to remove the stubs without tearing.

20 Another object of the invention is to provide a binder in which both ends of the clip are rigidly attached to the back.

A further object of the invention is to provide a clip binder of a simple and economical construction.

25 With these ends in view the invention embodies a binder having a clip which is constructed of a small tube bent in the shape of a U with roughened tacks placed through the back and into the ends of the tubes and 30 the ends of the tubes crimped around the tack.

Other features and advantages of the invention will be seen from the following description taken in connection with the drawings, wherein:

35 Figure 1 is a view showing the binder with the clips in place.

Figure 2 is a detail view showing the construction of one of the clips.

40 In the drawings I have shown my binder as it would be made wherein numeral 1 indicates the clip, numeral 2 the tack, and numeral 3 the binder.

The clips 1 are constructed of a small 45 piece of tubing bent in the shape of a U as shown in Figure 2 with the ends placed over the points 4 of the tack 2. The shanks 5 of the tacks are roughened as shown in Figure 2 so that when the ends of the tube 60 1 are crimped or bent as shown at the points 6 and 7 the tube will firmly grip the tack and thereby rigidly hold the ends of the clip to the back 8 of the binder.

It will be understood that changes may be made in the construction without departing from the spirit of the invention. One of which changes may be in the design of the clips; another may be in the use of any suitable number of clips; and still another may be in the design of the binder.

The construction will be readily understood from the foregoing description. To use the device the binder may be constructed with the checks or the like in place and it will be seen that it would be practically impossible to remove and replace any of the sheets without tearing them or destroying the binder. It will also be seen that this would provide a binder similar to a loose leaf binder in which all of the sheets may readily be examined all the way back and at the same time provide a binder of a very simple and economical construction.

Having thus fully described the invention, what I claim as new and desire to secure by Letters Patent, is:—

1. A binder, comprising a back, a plurality of leaves thereon, a tubular substantially U-shaped metallic clip carried by the back and having one leg only extending through registered perforations in the leaves, said leaves capable of being moved along said leg and turned over on to the other leg, and means for permanently securing each leg of the clip to said back including a roughened tack piercing the back with its head at the outer side of the back and its shank entering one of the tubular legs, and the leg being crimped into snug engagement with the roughened portion of the shank, the back being gripped snugly between the head of the tack and the bottom end of the leg.

2. As a new article of manufacture, a fastening device for the leaves of binders, comprising a substantially U-shaped tubular sheet metal clip, the end of each leg of the clip being open, and a pair of tacks capable of being inserted within the open ends of the respective legs, the shank of each tack being pointed at one end for piercing a binder-back, and said shank also being provided with a roughened portion on which a leg portion may be crimped.

LESTER C. GREEN.
